UNITED STATES PATENT OFFICE.

WILLIAM EWART HOLDEN, OF TAKAPUNA, NEAR AUCKLAND, NEW ZEALAND,
ASSIGNOR OF TWO-THIRDS TO THE NATIONAL PIANO COMPANY, LIMITED,
OF AUCKLAND, NEW ZEALAND, A CORPORATION OF NEW ZEALAND.

TRANSPOSING-PIANO.

1,236,435.

Specification of Letters Patent. Patented Aug. 14, 1917.

Application filed August 9, 1913. Serial No. 783,872.

To all whom it may concern:

Be it known that I, WILLIAM EWART HOLDEN, a subject of His Majesty the King of the United Kingdom of Great Britain and Ireland, resident of Takapuna, near the city of Auckland, in the Provincial District of Auckland and Dominion of New Zealand, have invented new and useful Improvements in Transposing-Pianos, of which the following is a specification.

The object of this invention is to enable a piano, whether overstrung, vertically strung, or obliquely strung, to be played in any one of two or more pitches as may be desired, according to the provision made in each particular case as to the number of pitches obtainable.

Referring to the drawings,

Figure 1 is a front elevation (shown broken) of the upper portion of an overstrung piano with the front removed, showing the action carriage specially mounted, and part of the action mounted therein, also the positions of extra strings, and the position of the means for moving the action carriage and key frame.

Fig. 2 is a longitudinal section of the bearing used in mounting the key frame on the key bed.

Fig. 3 shows in plan a means for moving the key frame and action carriage.

Fig. 4 is an elevation of one end of the action carriage showing the fixed bar or rail for mounting the dampers independently of the rest of the action, the bar or rail passing through the end of the action carriage and being secured permanently to the end of the piano.

Fig. 5 is a cross section of the action carriage and key frame.

Fig. 6 illustrates the positions of the extra strings, and the system of tuning employed in a four pitch piano, having a break or space occurring in the stringing.

The action 1 is of the usual type and is mounted within the action carriage 2, so as to be removable therefrom as a whole by disengaging the fastenings 2^b.

The action carriage 2 is mounted on and secured permanently to the back rail 2^a of the key frame 7, and is guided and kept rigid in its longitudinal movement by the brackets 6 sliding on the horizontal rods 5 attached to the sides 3 and 4 of the piano.

The key frame 7 is mounted on the key bed 8 by special bearings 9 in the front rail 7^a and the back rail 2^a. These bearings 9 (Fig. 2) while insuring rigidity of the key frame permit of the necessary longitudinal movement of the action carriage and key frame.

The thumbscrews 5^a provide means whereby the action carriage 2 and the key frame 7 may be locked against movement when the piano is being moved about or transported, also the two sets of brackets 6 to each rod 5 are necessary to insure the rigidity of the carriage.

The keys 9^a are mounted on the key frame 7 and operate the action 1 in the usual manner, the end keys 9^b being wider than the intermediate keys so as to leave no space between the key board and the sides 3 and 4 when the keys are moved.

The mounting of the key frame 7 on the key bed 8 is by the special bearings 9 (Fig. 2). These bearings 9 are equally spaced along the front rail 7^a and the back rail 2^a of the key frame 7 and are constituted as shown in Fig. 2. Each bearing consists of 80 rollers 42 journaled in either rail 7^a or 2^a, and the key bed 8 as shown, and a wearing plate 43 on the under surface of the rail for the lower roller 42 to work against. A covering plate 44 against which the upper roller 42 works is also used and is secured through slots 45 in either rail to the key bed 8 by screws. The slots 45 allow movement of the key frame in either direction, the lower roller 42 and plate 44 remaining stationary, while the top roller 42 and plate 43 move with the key frame.

In regard to the mounting of the hammer action within the action carriage 2, the action excepting the damper is mounted in the usual way on the action rail 18 and the rail 18 is supported in the end supports 56 (Fig. 1), so that the hammer action is removable as a whole from the action carriage 2.

In Figs. 1, 4 and 5 the action rail 18 is supported in the supports 56, but instead of the dampers 19 being mounted on the action rail 18, they are mounted on an independent rail 57, which latter passes freely through each end of the action carriage as illustrated in Fig. 4 and is secured permanently to the piano sides 3 and 4. The damper spoons 59 actuate the damper tails 60 in the same way

as before, but when the action carriage 2 is moved the dampers 19 remain stationary, and the rest of the action by reason of being mounted on the action rail 18 which travels with the action carriage 2, moves also and the damper spoons 59 shift from one damper tail to another.

The dampers operate on the same strings or sets of strings comprising note units each time and are not removable with the remainder of the action from the action carriage, also a damper is provided to each string, or set of strings, requiring a damper, independently of the number of hammers.

15 The extra rail 57 on which the dampers 19 are mounted does not interfere with the movement of the action carriage in any way, slots 58 (Figs. 4 and 5), being provided in the action carriage ends.

20 In Fig. 3 is shown a means for moving the key-frame 7 and with it the action carriage; the means consist of toothed racks 59 secured underneath the key frame 7 and with which gear or mesh pinions 60 on the 25 crank handle spindle 61. Means consisting of a hollow socket 62 with a groove or key way 63 cut therein, in which works a pin 64 on the spindle 61, and a ratchet wheel and pawl 65 for bringing the crank handle 66 back to and pushing same into the recess 67 to be out of sight when not required, are also provided. The handle 68 folds against the crank 66 before being pushed into the recess 67.

30 The extra stringing and the arrangement of tuned strings is a very material part of this invention, and is necessary to carry out the invention when it is applied to any piano where there is a break or space as before 35 stated occurring in the stringing.

40 Referring to Fig. 1 which shows the break or space 70 occurring in the stringing of an overstrung piano of two pitches only, it will be seen that string 71 is hammerless. This 45 string 71 is extra, that is to say, it is over and above the number of strings required in an ordinary or fixed pitch overstrung piano, and is tuned to the same pitch as string 72 of the section 73 of strings.

50 Following on this, it will be seen that if the hammers be shifted one string toward the right, (which equals a half tone), that string 72 will become hammerless, and string 71 that was hammerless will then be provided with a hammer and the result arising from this shifting of the hammers along the strings is that the piano is enabled to be played in a pitch half a tone higher than before.

55 60 It will also be noticed that string 74 of the section 73 of strings is also hammerless, this string 74 is also extra, that is to say, it is necessary to take hammer 75 when the latter is moved along a string. String 74 is tuned 65 consecutively or half a tone higher than

string 76 which would in a fixed or one pitch piano be the last string of the section 73 of strings.

For each extra pitch it is desired to obtain on an instrument having breaks or spaces in the stringing, it is necessary that an extra string be placed in the break, and an extra string be placed at one of the extreme ends of the ordinary stringing, as the case may be.

70 Referring to Fig. 6, the stringing and tuning of a piano having four different pitches is illustrated. In the case of an ordinary fixed or one pitch, piano string 78 would be the last string of section 78^a of strings, and string 83 would be the first string of the section 83^a of strings. The extra strings placed in the break are strings 80, 81, 82, string 80 being tuned to the same pitch as string 83, string 81 to the same pitch as string 84, and string 82 to the same pitch as string 85. 75 When playing in the lowest pitch, strings 80, 81, and 82 will be hammerless, and if the hammers be shifted one string along the instrument toward the right, then strings 81, 82 and 83 will be hammerless and the piano 80 will be set to a pitch a half tone higher than before and so on, until strings 83, 84 and 85 become hammerless, and strings 80, 81, and 82 are provided with hammers when the instrument will be then set to the highest 90 pitch obtainable, or a pitch three half tones higher than the lowest pitch, or when strings 86, 87 and 88 are hammerless. The three strings 86, 87 and 88 are also extra and are tuned consecutively at the upper end of the 95 section 88^a of strings, to enable the end hammers to move up the three strings. It will also be obvious in this instance as well, that to transpose in pianos where there are no breaks or spaces occurring in the stringing, 100 the extra strings are required only at either end of the ordinary strings, they to be tuned consecutively and the number to be determined according to how many pitches it is desirable should be obtainable on the instrument. 105

Having now fully described my invention, what I desire to claim and secure by Letters Patent is:—

1. An upright transposing piano having 115 a longitudinally movable key frame, a longitudinally movable action rail, carrying the hammers and hammer action, a longitudinally movable action carriage carrying the said action rail, a stationary damper rail, stationary dampers, and damper spoons movable with the hammer action. 120

2. An upright transposing piano having a longitudinally movable key frame, a longitudinally movable action carriage carrying 125 the hammers and hammer action, said action carriage being mounted on the key frame so as to move simultaneously therewith; a longitudinal hammer action rail carrying the hammers and hammer action, 130

mounted in said action carriage so as to be removable therefrom; a stationary damper rail carrying the dampers, and mounted between the piano sides; and damper spoons 5 movable longitudinally of the piano simultaneously with the hammers and hammer action.

3. An upright transposing piano having a longitudinally movable key frame to 10 which is attached a longitudinally movable action carriage, mounted on the keybed by means of bearings comprising an upper and a lower roller, an upper and a lower plate and screws passing through slots in the key 15 frame rails, for clamping the upper plate to the key bed, said action carriage being guided and kept rigid in its longitudinal movement by brackets on its top side working on horizontal rods secured to the piano 20 sides; a longitudinal hammer action rail carrying the hammers and hammer action removably secured in said action carriage; a stationary damper rail passing freely 25 through the action carriage ends; dampers stationary against movement longitudinally of the piano, and damper spoons attached to the hammer action.

4. An upright transposing piano having a longitudinal key frame to which is attached a longitudinally movable action carriage carrying a longitudinally movable hammer action rail on which is mounted the hammers and hammer action; said hammer 30 action rail, the hammers and the hammer

action being removable as a whole from said 35 action carriage; a stationary damper rail mounted between the piano sides and passing freely through said action carriage ends; dampers stationary against longitudinal movement within the piano; damper 40 spoons attached to the hammer action and movable from one damper tail to another and rack and pinion gear for imparting longitudinal movement to the key frame and action carriage. 45

5. An upright transposing piano having a longitudinally movable key frame to which is attached a longitudinally movable action carriage carrying a longitudinal hammer action rail on which are mounted the 50 hammers and hammer action; said hammer action rail, the hammers and the hammer action being removable as a whole from said action carriage; a stationary damper rail passing freely through said action carriage ends; dampers stationary against longitudinal movement within the piano; damper spoons attached to the hammer action and movable from one damper tail to another, rack and pinion gear for imparting 55 longitudinal movement to the key frame and action carriage; the stringing having a break and extra strings placed in said break. 60
